[57] CLAIM

The ornamental design for an electronic module enclosure, as shown and described.

DESCRIPTION

FIG. 1 is a perspective view of an electronic module enclosure showing our new design;

FIG. 2 is a right side elevational view thereof;

FIG. 3 is a top plan view thereof;

FIG. 4 is a front elevational view thereof;

FIG. 5 is a rear elevational view thereof;

FIG. 6 is a perspective view of a second embodiment thereof;

FIG. 7 is a right side view thereof;

FIG. 8 is a top plan view thereof;

FIG. 9 is a front elevational view thereof; and,

FIG. 10 is a rear elevational view thereof.

The undisclosed left side and bottom views of the first and second embodiments are identical to the right side and top views shown.
